MACHINE FOR MAKING HORSESHOES.

No. 450,375.

Patented Apr. 14, 1891.

UNITED STATES PATENT OFFICE.

ZACHARIAH V. PURDY, OF VIENNA, VIRGINIA.

MACHINE FOR MAKING HORSESHOES.

SPECIFICATION forming part of Letters Patent No. 450,375, dated April 14, 1891.

Application filed August 26, 1890. Serial No. 363,078. (No model.)

To all whom it may concern:

Be it known that I, ZACHARIAH V. PURDY, a citizen of the United States, residing at Vienna, in the county of Fairfax and State 5 of Virginia, have invented certain new and useful Improvements in Machines for Making Horse and Mule Shoes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates especially to that class of horseshoe-machines in which the blank is bent around a stationary block or "former" by movable jaws, and has for its objects to simplify the construction and operation, to 20 provide for easy adjustments to enable different-sized shoes to be made on the same machine, to increase the durability of the machine, and to enable the different parts when worn or broken to be conveniently and 25 expeditiously renewed or replaced.

To these ends the invention consists in the construction, arrangement, and combination of parts, as will be hereinafter fully described, and particularly pointed out in the appended 30 claims.

In the accompanying drawings, which illustrate my invention and form a part of this specification, Figure 1 is a plan view of the machine, one end being broken away. Fig. 35 2 is a longitudinal vertical section on the line *a b*, Fig. 1. Fig. 3 is a transverse vertical section on the line *c d*, Fig. 1. Fig. 4 is a plan view of one end of the machine with the guide-rails removed and a part of the upper 40 plate of the reciprocating-jaw carriage broken away to show the bending jaws. Fig. 5 shows in plan and transverse section the upper plate of the jaw-carriage. Fig. 6 is a plan view of the springs with their holder for holding the 45 bending jaws apart. Fig. 7 is a plan and side view of the coupling for connecting the jaw-carriage with the yoke of the driving-eccentric. Fig. 8 is a view of the adjustable cams for operating the cutters, by which the shoe- 50 blanks are separated from the bar, with the

means for adjusting the same upon the shaft. Fig. 9 shows in front, side, and plan views the cutter-holder with the cutter for severing the shoe-blank from the bar; and Fig. 10 is a perspective view of the cutter last above referred to. 55

My machine is a double machine provided with two sets of shoe-forming devices, both connected with and operated by a main driving-shaft, so that two shoes may be formed 60 during each complete revolution of the shaft, one by each set of devices. The two sets of forming devices are located on opposite sides of the driving-shaft and are both alike, so that a description of one set will answer for 65 both.

The frame of the machine comprises two parallel side rails 11, connected at both ends by cross-ties or tables 22.

3 designates the driving-shaft, which is 70 mounted centrally and transversely upon the side rails in suitable boxes or bearings 44. Upon this shaft, centrally between the side rails, is fixed an eccentric 5, which works in a yoke 6, to which the operating mechanisms 75 of the machine are connected, so as to be reciprocated thereby. The yoke 6 may be constructed, as usual, to closely fit the eccentric all around; but in order to reduce the friction between the yoke and eccentric to a minimum 80 and also to avoid the rising and falling movements of a closely-fitting yoke, I construct it, as shown in the drawings, of two vertical parallel bars *e f*, connected by cross bars or plates *g h*. By this construction the eccentric, instead of having frictional contact all around, 85 has contact with the yoke only at two diametrically-opposite points, and if made sufficiently loose only at one point during the movement of the yoke in either direction. 90

7 designates a flat plate, which lies between the side rails 11, being supported by horizontal ribs or shoulders 88 on the inner sides of the rails and capable of reciprocating longitudinally thereon. At the center it has an 95 opening 9, into which the lower end of the yoke 6 projects and fits. The plate 7 and the yoke 6 are connected together by a coupling, which consists of a flat plate 10, from the upper face of which rises a vertical standard 11. 100

The plate 10 is bolted against the under side of the plate 7, the standard projecting up through the same and bolted to a lug 12 on the yoke.

5 Upon the upper side of the plate 7 is bolted a plate 13, with a short separating-plate 14 between the two to hold them apart. The plate 13 extends from the yoke 6 forward nearly to the end of the plate 7, and the thickness of 10 the separating-plate is such as to provide suitable space between the front ends of the two plates 7 13 for the bending-jaws 15 15, which are pivoted therein by bolts 16 16, passing through both of said plates. The jaws are 15 capable of swinging toward and from each other, and are normally held apart by springs 17 17, set into the front edge of the separating-plate 14, their free or swinging ends lying against the inner sides of the side rails 1 1 of 20 the frame.

18 is the former, upon or around which the shoe-blank is bent to form the shoe. It is formed on or attached to the end of an arm 19 projecting back from a plate 20, which is 25 adjustably bolted upon the cross-tie or table 2 of the frame, so as to be capable of being moved forward or back in the line of the length of the machine. The former stands at such height that it will enter the space between 30 the two plates 7 13, in which the jaws 15 15 are pivoted, the latter passing on either side thereof in their forward movement.

Cams 21 21 are adjustably set into the side rails of the machine at points opposite each 35 other and in line with the former. These are for the purpose of forcing the jaws 15 15 toward each other to press the ends of the blank in and around the former, the said cams being so set and arranged that the inward movement 40 of the jaws will commence as soon as the widest part of the former is passed. Their size and shape must of course be such as to press the blank tightly against the former and give the desired exterior finish to the completed shoe. By making these cams adjustable they may be set to compress and thicken 45 the heels of the shoes more or less, as may be desired, and may also be adjusted to formers of different sizes or shapes, whereby the same 50 machine is adapted to make shoes of different sizes or shapes by merely changing the former and adjusting the cams.

In order to avoid friction between the jaws and the blank in the operation of bending 55 and forming, the shoe-rollers 22 are loosely set into open seats formed in the inner sides of the jaws at their front ends. The walls of these roller-seats form something more than semicircles, so as to hold the rollers and prevent 60 them from escaping, yet exposing enough of their cylindrical surfaces and allowing them to project beyond the jaws far enough to roll along upon the blank. By seating them in the jaws in this manner I am enabled to 65 use rollers of a length to fill the entire space between the plates 7 13, and so avoid the feather-edge liable otherwise to be formed on

the shoe. As a further means for retaining the rollers in place, they are formed with short journals 23, which project into and run in 70 curved guideways 24, formed in the plates 7 and 13. The plate 13 is wider than the space between the side rails 1 1, so that its side edges project out and run upon said rails. It is held down by guide-plates 25, which are 75 bolted upon the side rails with spacing-blocks 26 between, and is held against lateral movement by shoulders formed on its upper side, which run against said guide-plates.

To prevent the blank from twisting or buckling, I mount a roller 27 on the front end of the plate 13, which roller projects down slightly through an opening in the plate, so that the blank is rolled and pressed flat while being bent by the jaws, and again during the 85 backward movement of the parts after the shoe has been formed.

In operating this machine I propose to use blanks previously prepared in the bar, but not separated from each other, and to adapt it to 90 the use of blanks so prepared I provide a cutter, which is operated by a cam on the shaft 3. 28 designates the cutter, which is formed, as shown in Figs. 9 and 10, with a vertical stem *m*, by which it is connected with the 95 cutter-holder 29. This cutter-holder is formed as shown in Fig. 9, and is connected with the end of a lever 30, fulcrumed in a standard 100 31, bolted upon the guide-plate 25. It has a horizontal arm *n*, in which is formed an elongated 105 opening *o*, which receives the stem *m* of the cutter, the latter being held by a set-screw 32. The opening *o* is elongated for the purpose of permitting an adjustment of the cutter to cut off longer or shorter blanks. This 110 adjustment is effected by means of blocks (not shown in the drawings) dropped in or removed from behind the stem of the cutter. On the opposite side of the machine, directly across from the cutter, is a gage 33, adjustable 115 in and out, and held in adjusted position by a set-screw, which sets upon a horizontal arm under the guide-plate 25.

The guide-plate 25 on the side of the machine on which the cutter is located is made 115 in two parts, (see Fig. 1,) which are sufficiently separated to form a feed-opening 34, through which the blank is introduced into the machine, either by dropping it down from above or by pushing it in endwise from the side. 120 It is pushed across until it abuts against the gage 33, which has been set to correspond with the adjustment of the cutter, so that the middle of the blank will be opposite the center of the former when the cutter descends to 125 sever the blank from the bar.

The feed-opening 34 is extended downward to the plane of the plate 7 by cutting a channel 35 in the side rail 1 in order that the blank may lie flat upon said plate when it is 130 cut off from the bar and in position to be caught by the former when the plates and jaws carry it forward.

As shown in Fig. 1, the plate 7 extends for-

ward slightly past the end of the former and forms a table or support for the blank when the latter is placed in the machine. At the center the plate is cut out to form an open space between it and the former, through which opening the shoe is discharged from the former upon an inclined chute 36, which conveys it out and away from the machine.

Fig. 8 illustrates the parts of a double adjustable cam for operating the cutters at the two ends of the machine. These cams require to be so adjusted relatively to the levers 30, which carry the cutters, that the levers will be tripped and the cutter at either end of the machine operated at the instant when the forming mechanism at that end is at the limit of its backward movement and while it is at rest, or just as it begins its forward movement. To provide for effecting such adjustment quickly and conveniently and for changing the same when required, I construct the cams as shown.

37 is a disk or plate, which is keyed upon the shaft 3.

38 39 are the two cams, (one for each cutter-lever,) which are also placed upon the shaft on opposite sides of the disk 37 and clamped to the same by clamping-bolts, which pass through bolt-openings in the several parts. The bolt-openings in the cams are elongated and curved, as shown, to permit angular adjustment of the cams relatively to the disk 37 and to each other.

The former is beveled downward and inward—that is, it is smaller at its lower face than at its upper—as indicated in Fig. 2. This is for the purpose of facilitating the removal therefrom of the formed shoe. As soon as the shoe begins to chill (it is to be here understood that the blanks are to be fed into the machine hot, approximately at a white heat) it begins to contract, and this contraction, by reason of the taper or bevel of the former, tends to draw the shoe off the same and to discharge it therefrom automatically. The chilling of the shoe may be instantaneously effected by throwing water upon the same at the instant when it is ready to be removed from the former. A water-supply pipe 50 may be so connected with the machine that the flow of water will be automatically controlled and directed upon the shoe at the proper time by some moving part of the machine. This, however, forms no part of the present invention and need not, therefore, be illustrated or further described herein.

A designates the bed-frame upon which the machine is mounted.

Power may be applied to the machine 60 through any ordinary or suitable driving-gear. In the drawings I show a pinion B, mounted in a bracket C, bolted to the base-frame. The pinion B meshes with a gear-wheel D on the end of the shaft 3. On the 65 shaft of the pinion is a wheel or pulley E,

through which power is applied. The bracket C may be bolted to the side rail of the machine, if preferred, it being shown bolted to the base-frame merely for convenience of illustration.

Having now described my invention, I claim—

1. In a horseshoe-machine, the combination of a fixed former, a revolving shaft and an eccentric thereon, an eccentric yoke, a sliding carriage comprising two plates secured together and to the yoke, and two jaws pivoted between said plates in position to pass on opposite sides of the former and capable of swinging toward and from each other, substantially as shown and described. 70

2. In a horseshoe-machine, the combination of a fixed former, a revolving shaft and an eccentric thereon, an eccentric yoke, a sliding carriage comprising two plates secured together and to the yoke, two jaws pivoted between said plates in position to pass on opposite sides of the former and capable of swinging toward and from each other, and cam-guides on the frame of the machine to force the jaws toward each other, substantially as shown and described. 85

3. In a horseshoe-machine, the combination, with the fixed former and with the movable bending-jaws, of a roller 27, journaled in the 95 jaw-carriage and adapted to roll and flatten the blank, substantially as shown and described.

4. In a horseshoe-machine, the combination, with the driving-shaft and a cam thereon, of a lever 30, fulcrumed on the frame of the machine with one end in the path of said cam so as to be vibrated thereby, and a cutter on the opposite end of the lever adapted to sever blanks from the bar after the same has been 105 fed into the machine, substantially as shown and described.

5. In a horseshoe-machine, the combination, with the bending devices, of a former tapering toward its lower or delivery side, substantially as shown and described. 110

6. In a horseshoe-machine, the combination, with the reciprocating forming or bending jaws, of a former mounted on the frame of the machine and longitudinally adjustable 115 thereon, substantially as shown and described.

7. The double adjustable cam herein shown and described, the same comprising a central plate or disk 37, keyed upon the driving-shaft, 120 and the cam-plates 38 39 clamped to said central disk on opposite sides and independently adjustable thereon.

In testimony whereof I affix my signature in presence of two witnesses.

ZACHARIAH V. PURDY.
